COMBINED SEWING MACHINE CABINET AND
STOOL THEREFOR

Edward K. Raichert, Arlington Heights, Ill., assignee to Roman Raichert Company, Chicago, Ill., a corporation of Illinois

Application September 6, 1949, Serial No. 4,864

Term of patent 14 years

(Cl. D33—12)

To all whom it may concern:

Be it known that I, Edward K. Raichert, a citizen of the United States, residing at Arlington Heights, in the county of Cook and State of Illinois, have invented a new, original, and ornamental Design for a Combined Sewing Machine Cabinet and Stool Therefor, of which the following is a specification, reference being made to the accompanying drawing forming a part hereof.

In the drawing:

Fig. 1 is a perspective view showing in closed position the combined sewing machine cabinet and stool therefor embodying my new design;

Fig. 2 is a perspective view showing the combined sewing machine cabinet and the stool therefor, with the stool separated from the cabinet and the top door for the sewing machine cabinet in open position;

Fig. 3 is a perspective view of the stool shown in Fig. 2 and as seen from the lower right-hand corner in Fig. 2.

I claim:

The ornamental design for a combined sewing

machine cabinet and stool therefor, substantially as shown.

EDWARD K. RAICHERT.
